UNITED STATES PATENT OFFICE

2,411,291

ADJUSTABLE DIE

Emil L. Ramstedt, New Haven, Conn., assignor to
The American Steel and Wire Company of New
Jersey, a corporation of New Jersey

Application May 1, 1945, Serial No. 591,391

6 Claims. (Cl. 57—138)

1

The present invention relates to wire rope or cable laying machines, and particularly to improvements in the guide die for the center strand or core of a rope or cable to be formed on such machines.

On certain known types of ropes or cables, it is necessary to provide a center strand or core of substantially triangular cross-sectional contour. Heretofore in the guiding of such a triangular strand or core, it has been the practice to employ a guide die having a triangular bore or passage-way extending therethrough, this bore usually having been formed by a broaching operation. According to prior practice a separate guide die must be used for guiding each size of strand or core. This necessitates the provision of a great number of dies. Since they are usually made from high-grade tool steel which is hardened and polished and which must be carefully initially broached, their initial cost is thus very high and they are also costly to maintain.

Among the disadvantages inherent in prior art guide dies are: the tendency of a bent core wire to cause a break; the tendency toward breakage on the introduction of an oversized core wire; the tendency of the die to wear out rapidly; the excessive original cost of producing the dies; the tendency of worn dies to objectionably shave the wire core; the tendency of the die to overheat; and the tendency to mutilate the apexes of the triangular core.

Among the objects of the present invention are to overcome the above and related disadvantages of prior practice and to provide a simplified core guiding die comprising a holder having a plurality of steel balls mounted therein with provision for radial adjustment, the balls being adapted to jointly define a die opening to suit the contour of various sizes of wires or cores.

The above and related features of the invention will be fully apparent from the following detailed disclosure when read in connection with the accompanying drawings and the appended claims.

In the drawings:

Figure 1 is a plan view of a portion of a rope or cable laying machine having my invention incorporated therein.

Figure 2 is an enlarged axial section through the guide die constituting the chief feature of the present invention.

Figure 3 is a transverse section on line III—III of Figure 2.

Figure 4 is a perspective view of a triangular

2

wire or core adapted to be guided by the die of the present invention.

Referring more particularly to the drawings, reference numerals 10 represent disc-like members of a conventional form of a rope or cable laying flier, this flier being rotatably supported in a manner well known to those skilled in the art. The flier includes a plurality of cradles 12 mounted by suitable trunnions journaled in the disc-like members 10. Each cradle 12 carries a reel 14 carrying a supply of rope or cable strand material 16. The several disc-like members 10 are secured to an elongated hollow tubular member 18 a portion of which extends through a suitable bearing (not shown) in which it is rotatably mounted. At its forward end the member 18 carries a known form of lay plate 22 through which the several strand elements 16 converge toward a rotary stranding die 24 of conventional form.

A countershaft 26 mounted in suitable bearings 28 is driven by a suitable main drive motor (not shown). This shaft drives the hollow member 18 through conventional transmission elements 25 (not shown), thus providing a drive for the flier. The rotary stranding die 24 is driven by a belt 40 from pulley 42 carried on a stub shaft 44 driven by change gearing 46 from a gear 48 secured to the countershaft 26. A pair of haul-off drums 50 and 52 of conventional form are provided to draw the rope or cable through the machine, the drum 52 being mounted on a shaft carrying a gear 54 driven by a pinion 56 secured to a shaft 58 driven through reversing gearing 60 and change gears 62—64 from the countershaft. The shaft 58 carries a pulley 66 which through belt 68 drives pulley 70 carried by shaft 72 which is connected by gearing 74 to a shaft 76 which carries a take-up drum 78 on which is accumulated the product of the machine.

Extending longitudinally through the center of the hollow flier member 18 and rotatable relatively thereto is an elongated hollow shaft 80 which is adapted to be driven in a direction opposite to the direction of rotation of the flier.

A cradle (not shown) rotatably supports a suitable reel which carries a supply of triangular wire or core strand such as indicated at 108. This core strand passes longitudinally through the hollow center of the shaft 80. As the flier rotates, the plurality of strands 16 is laid around the triangular core 108 which is rotated at a speed to suit the lay of the rope or cable being laid up by the machine.

A particular feature of the present invention

relates to the simple and improved inexpensive guide bearing for the triangular core 108 which is effective to impart a twist to the core in a direction to suit the lay of the rope being formed. As shown in Figure 2, the guide die includes a 5 holder portion 112 having a circular passageway 114 extending therethrough. The holder is provided with an enlargement or collar portion 116 carrying end projections 118 which interfit with notches 120 formed in the extremity of a sleeve 122 which telescopically engages the end of the bore of the hollow shaft 80, the sleeve 122 being detachably secured to the shaft by a set screw 124. An internally threaded coupling nut 126 engages threads formed on the extremity of the 10 sleeve 122 and coacts with the collar 116 on the holder 112 to thus detachably secure the guide die to the sleeve 122. The entrance end of the holder 112 is flared outwardly, as indicated at 128, to facilitate initially threading the core through the die. A plurality of radial holes 130 are formed in the holder 112, with the axis of each substantially perpendicular to the longitudinal axis of the die passageway 114. The outer portions of the holes 130 are provided with respective screw threads 132, and there is a 15 respectively hardened steel ball 134 in each hole 130. Balls of various sizes, such as those of hardened tool steel forming conventional ball bearings, are satisfactory and economical. Outward movement of the balls 134 is prevented by screw plugs 136 which have socket portions 138 formed therein for engagement with a suitable adjusting wrench 140. Each plug 136 is preferably formed with a shallow conical depression 142 forming a self-centering seat for the ball coacting therewith. In the embodiment illustrated, the holder 112 is formed with three radial holes 130 circularly arranged and equidistantly spaced with a respective ball in each hole. The screw plugs 136 constitute means for adjusting the position of the balls radially within the holes, thus making it possible for a given die equipped with three identical balls to be used for guiding different sizes of substantially triangular wire or core such as shown in detail in Figure 4. By simply adjusting the screw plugs 136, the size of the substantially triangular guide opening jointly formed by the three balls can be easily and quickly varied to suit the size or gauge of triangular core wire used for different sizes of ropes or cables. Thus my improved die overcomes the objections to prior art dies, and in addition, practice demonstrates that a minimum number of dies will cover the entire range of sizes usually required by manufacturers of flattened strand or rope. When the balls 134 become worn after long use, they can be inexpensively replaced, and in order to make such replacement it will be unnecessary to remove the wire in process from the die. Nor will it be necessary to cut the core wire. And because the balls are universally rotatable, wear is distributed and heat due to friction is greatly minimized or practically eliminated. Thus those

skilled in the art will appreciate that the invention is a definite step forward over prior conventional practice.

Having thus described the invention, what I desire to secure by Letters Patent is defined in the appended claims.

I claim:

1. A rope or cable laying machine of the character described, comprising a core guide die including a holder having a plurality of holes whose axes converge to a common point, and a respective ball mounted in each hole with provision for radial adjustment, the said balls jointly defining an opening adapted to form a guide for different sizes of core strand.

2. A rope or cable laying machine of the character described, comprising a core guide die including a holder, a plurality of holes whose axes converge to a common point, a respective ball occupying each radial hole formed in the holder, and means for adjusting each ball radially in the hole it occupies to suit different sizes of core strand.

3. In a machine of the class described, a guide die comprising a holder having three equidistant circularly spaced holes therein, a respective ball in each of said holes, and respective means for adjusting each ball radially within the hole it occupies to suit different sizes of substantially triangular core strand.

4. A guide die comprising a holder having a longitudinally extending passageway, a plurality of radial holes whose axes intersect at a common point on the longitudinal axis of said passageway, a respective ball within each of said holes, the several balls jointly defining a curvilinear die opening, and means engaging said balls for adjusting them radially within said holes to suit different sizes of cores.

5. A guide die comprising a holder having a passageway extending longitudinally thereof, three equiangularly spaced holes whose axes intersect the longitudinal axis of said passageway, a respective hardened steel ball within each hole, the balls thus jointly defining a substantially triangular guide opening, and plugs adjustable relatively to the holder and having seats engaging the balls to position them for coaction with different sizes of triangular core strands.

6. A guide die comprising a holder having a passageway extending longitudinally thereof, three equiangularly spaced holes whose axes intersect the longitudinal axis of said passageway, a respective hardened steel ball within each hole, the balls thus jointly defining a substantially triangular guide opening, the outer portions of each of said holes being formed with internal screw threads, and screw plugs engaging said threads and having recessed seats engaging said balls, said plugs being adapted to adjust the balls radially to suit different sizes of triangular core strands.

EMIL L. RAMSTEDT.
